United States Patent Office

Des. 221,779
Patented Sept. 7, 1971

221,779

DESK

Douglas Deeds, San Diego, and Barry L. Rosengrant, Los Angeles, Calif., assignors to Architectural Fiberglass, Inc., Los Angeles, Calif.

Filed Jan. 19, 1970, Ser. No. 20,967

Term of patent 14 years

Int. Cl. D6—01

U.S. Cl. D33—7

FIG. 1 is a perspective view of the desk embodying our new design taken from the front and to one side;

FIG. 2 is a perspective view taken from the back and the other side;

FIG. 3 is a right side elevational view; and

FIG. 4 is a left side elevational view.

We claim:

The ornamental design for a desk, substantially as shown.
